Attorney

UNITED STATES PATENT OFFICE.

GERTRUDE VAN GIESEN GRANGER, OF SAVANNAH, GEORGIA.

RUG BAG.

REISSUED

Application filed July 17, 1925. Serial No. 44,327.

To all whom it may concern:

Be it known that I, GERTRUDE VAN GIESEN GRANGER, a citizen of the United States, residing at Savannah, in the county of Chat-
ham and State of Georgia, have invented
certain new and useful Improvements in
Rug Bags; and I do hereby declare the fol-
lowing to be a full, clear, and exact descrip-
tion of the invention, such as will enable
others skilled in the art to which it apper-
tains to make and use the same.

This invention relates to improvements in
bags, more specifically moth-proof rug bags.

The object of the bag is to furnish the
housewife with a convenient receptacle in
which to place her rugs while not in use
and thus protect them from dust and de-
structive insects, such as moths. Briefly
stated, the use of the bag is as follows:

The rug to be protected is rolled on a
pole, the bag opened and the rug placed
therein. The bag carries a permanently
attached top, with a reinforced segment in
back which acts as a hinge, with closure
means for placing the bag in a moth-proof,
dust-proof condition.

The novelty of the bag lies chiefly in
using a section of the bag as a hinge for
the top.

A further improvement is mounting the
closure means on beading, the beading in
turn being mounted on tape which, in turn,
is mounted on the bag in such a way as to
allow the edge of the bag to project up
into the top and so make a dust-proof, moth-
proof joint.

Other novelty lies in the use of a triangu-
lar clasp in the corner of the opening of
the bag, so as to keep the bag, when the
bag is not drawn shut, in a semi-open pos-
ition, which facilitates the placing of rugs
therein.

In the drawings,

Fig. 1 is a perspective of the bag in opened
position, with the rug partly inserted
therein.

Fig. 2 is a rear elevation showing the
bag in a semi-closed position with a part
of the rear broken away.

Fig. 3 is a plan view of fastener carrying 50
tapes.

Fig. 4 is a fragmentary cross-sectional
view drawn through the top, tape and
fastener.

As shown in Fig. 1, the invention com- 55
prises a bag 1, open, with top 2 held in
position by segment of the bag 3, used as
a hinge to swing the top into a closed posi-
tion when the bag is desired to be shut.

Top 2 is in such relative position as to 60
allow the edge of bag 4 to project beyond
the closure means 11 and thus prevent dust
and insects from entering when the bag is
in a closed position and also protects the 65
contents of the bag from chafing on the closure
means 11.

The top 2 is fastened to a tape 6, which
runs around the bottom of the top to the
side of hinged section 3. A similar tape
continues around the bag below top 4, as 70
at 5. Each of these tapes are secured to
the top and bag respectively, by a line of
stitching adjacent its lower edge, so that
the adjacent edges of tapes are left free.
On the free edges of these tapes is mounted 75

closure means 10 and 11. At the juncture
of the tapes 6 and 5, adjacent to the hinge
3 is a triangular shaped clasp 9, which serves
to keep the bag 1 in a semi-opened condition
when the fastening means 10 and 11 is not 80
drawn shut the triangular metal clasp acts
as a wedge, the point of the triangle posi-
tioned in the corner of the opening of the
bag. When the closure means is not in
operation, the bag will be kept in a semi- 85

open position by said clasp acting as a
wedge. This facilitates the placing of rugs
in the bag and yet when the bag is in a
closed position presents no opening for
moths or other insects to enter as the flap 90
on the inside will cover any crevice left. A
name plate 15 is shown in connection with
bag 1.

In Fig. 2, hinged section 3 is shown rein- 95
forced by an interlocking of the folds of
the cloth in the form of a seam. The closure
means 10 and 11 is operated by a pulling
member 14.

2

In Fig. 3, tapes 6 and 5 which are fastened on the top 2 and bag 4 as described, show attached to the edges of tapes, beading 12 and 13 respectively, upon which closing means is strung.

In Fig. 4, the top 2 is shown attached to tape 6, and the beading 12 attached thereto, with the closing means attached thereto.

What I claim is:

In a tubular bag, a top, the top attached to the bag by means of a section of the bag, said section acting as a hinge, a closure means, the closure means having a triangular clasp between the edges of the closure means in order to keep the bag in a semi- 15 open position.

In testimony whereof I affix my signature.

GERTRUDE VAN GIESEN GRANGER.
